H. A. W. WOOD.
METHOD OF SHAVING STEREOTYPE PRINTING FLATES,
APPLICATION FILED MAY 20, 1915.

UNITED STATES PATENT OFFICE.

HENRY A. WISE WOOD, OF NEW YORK, N. Y., ASSIGNEE TO WOOD NEWSPAPER MACHINERY CORPORATION, OF NEW YORK, N. Y., A CORPORATION OF VIRGINIA.

METHOD OF SHAVING STEREOTYPE PRINTING-PLATES.

1,216,388.

Specification of Letters Patent. Patented Feb. 20, 1917.

Application filed May 20, 1915. Serial No. 29,319.

To all whom it may concern:

Be it known that I, HENRY A. WISE WOOD, a citizen of the United States, residing at New York, in the county of New York and State of New York, have invented a new and useful Method of Shaving Stereotype Printing-Plates, of which the following is a specification.

This invention relates to a method of finishing stereotype plates on the back and the principal objects thereof are to provide for preventing distortion of the plate by the shaving operation and especially for preventing the flattening out of the portions of the plate which are provided with elevations on their printing surfaces.

Reference is to be had to the accompanying drawing which is a sectional perspective view of the shaving arch of a machine for finishing a semi-cylindrical stereotype printing plate shown as provided with means for carrying out the method which is the subject of this invention.

As is well understood, all stereotype plates for newspapers are shaved to thickness, the plate, if a curved one, being held against a smooth semi-cylindrical arch for this purpose. Recently it has come to be the practice to make half-tone cuts in varying heights. In this case the foreground and the solids are forced above the surface of the plate so that they are higher than the back-ground and the high lights of the plate. As these higher portions bring to bear more pressure on the sheet than the light portions they print more distinctly. In this way the foreground and solid portions of the picture are sharp and black, whereas the background and high lights are less clear cut and appear gray. However, owing to the fact that the usual method of shaving plates has been retained in connection with plates made as described above, the pressed-up effect referred to is destroyed in shaving. This is due to the following facts:

The matrix is usually made of paper which has been molded from the page of type by means of a felt blanket pressed against the type. After being molded, the matrix is dried in contact with the type and when removed it is found that the pressed-up portions of the half-tone have been precisely reproduced in the face of the matrix, which is what is required, but it

is also found that these pressed-up portions show on the back as well. In other words, where there is a depression on the face of the matrix, there is a corresponding projecting field on the back having substantially the same shape as the depression on the front side. Now when this matrix goes into the casting box and a plate is made from it, it is obvious that the metal bears against the inside face of the matrix with considerable pressure. Therefore, these projections or depressions become somewhat flattened and equalized. This naturally reduces the pressed-up effect but still some of this effect remains and is found in the cast plate. But when the cast plate goes to the shaving machine in a flaccid condition, as it should, the shaving knife, which is invariably made dull, forces these pressed-up portions of the plate so hard against the shaving arch that they become flattened or otherwise marred.

It is the object of this invention to avoid these difficulties due to the shaving operation. This invention relates solely to the shaving operation.

Referring now to the drawing, it will be seen that the semi-cylindrical plate A is shown in an arch B of the usual type. A shaving knife C is shown on a rotating knife carriage D. The plate is shown as supported on rollers F and a lifting clamp G, as is the usual practice. The plate is shown as provided with the usual finishing strips H and the knife C is shown in the act of shaving off these strips to a uniform semi-cylindrical shape in order that the interior of the plate may fit the printing cylinder of the press. As so far described in this paragraph, these features are old.

In order to preserve the pressed-up portions of the plate from being flattened or otherwise marred, I insert into the shaving arch B with the plate a backer M. This backer may be the matrix from which the plate was cast, or a duplicate thereof, but at any rate, it occupies the exact position on the plate occupied by the casting matrix during the casting operation. In this way the projections m and depressions m' of the concave surface of the matrix fit respectively the depressions a and the projections a' on the convex surface of the plate.

Although I have referred to depressions on the matrix and projections on the plate,

it is to be understood that these are merely relative terms, as they really represent the normal surfaces of these two parts, that is, the surfaces as they would be without the 5 alteration due to the half-tone process, as carried out at present. This matrix, therefore, lies between the plate and the arch during the process of shaving and prevents the distortion or marring of the plate by pressure 10 on it from within. Therefore, all the pressed-up effect is preserved in the plate and the plate will emerge from the arch in the condition on its type face in which it entered it. This is an important feature because it 15 permits of the preservation of the additional distinctness secured by the above-mentioned method.

It will be understood, of course, that while I have called this backing-up sheet 20 a matrix, it can be a true matrix or a dummy matrix, having the main characteristics of the matrix but not necessarily exactly duplicating all the more minute depressions and projections thereof, if it is found convenient 25 to make such a dummy matrix. Even in that case the varying heights above mentioned, are reproduced on the dummy, of course. If a dummy or duplicate is used, the casting operation can proceed while the 30 shaving operation is going on, thus saving a material amount of time.

Although I have shown and described the method as used in connection with a shaving arch, it is to be understood that it 35 is within the scope of the invention as expressed in the claims to carry out the method without any shaving arch, as that term is understood. For example, the method can be applied to flat plates, and can be carried 40 out in apparatus such as shown in my applications, Serial Nos. 18,733 and 18,248, filed March 11th and March 31st, 1915, respectively.

It will be seen, therefore, that the difficulties above mentioned are entirely counteracted by this method without adding materially to the expense thereof and that the

method which is the subject of this invention (although designed for use in connection with plates for the production of half-tone cuts) is not limited thereto and can be used for the purpose of preserving any delicate or rough irregularities of a printing plate of any kind. Therefore, I do not wish to be limited to the exact application of the 55 method herein shown and described except as defined in the appended claims, but what I do claim is:—

1. The method of preserving the various heights of a printing plate during the process of shaving the back thereof, which consists in interposing between the printing side of the plate and the surface against which it rests during shaving, a backer which fits substantially in the depressions 65 and projections on the printing face of the plate, and shaving the back side of the plate while held in that condition.

2. The method of shaving a printing plate, which consists in applying to the printing 70 surface thereof a duplicate of the matrix on which it is cast, forcing the plate with said duplicate against a surface having the same general shape as the plate, and shaving the rear side of the plate while held in 75 that condition.

3. The method of shaving a semi-cylindrical stereotype printing plate, which consists in applying to it a matrix on the type 80 face thereof, said matrix fitting the type surface of the plate, moving the plate and matrix into a curved shaving arch having a smooth semi-cylindrical inner surface, pressing the plate with the matrix thereon against said arch, and shaving the surfaces 85 of the finishing strips on the back of the plate while the plate is held in the arch.

In testimony whereof I have hereunto set my hand, in the presence of a subscribing witness.

HENRY A. WISE WOOD.

Witness:

BLODWIN W. JONES.
